UNITED STATES PATENT OFFICE.

JAMES K. WHITESIDE, OF RISING SUN, MARYLAND.

IMPROVED WASHING-MACHINE.

Specification forming part of Letters Patent No. 36,582, dated September 30, 1862.

To all whom it may concern:

Be it known that I, JAMES K. WHITESIDE, of Rising Sun, in the county of Cecil and State of Maryland, have invented a certain new and useful Improvement in Machines for Washing Clothes; and I do hereby declare the following to be a full, clear, and exact description of the construction and operation of the same, reference being had to the accompanying drawings, making a part of this specification, in which—

Figure 1 represents a perspective view of the machine with the lids or cover thrown open to show the interior of the machine. Fig. 2 represents a longitudinal vertical section taken centrally through the machine. Fig. 3 represents a horizontal section taken through the box or tub, to show a portion of the interior not distinctly shown in the other figures.

Similar letters of reference, where they occur in the separate figures, denote like parts of the machine in all cases.

To enable those skilled in the art to make and use my invention, I will proceed to describe the same with reference to the drawings.

A represents a wash-box supported upon legs B, set upon rockers C, for the purpose of operating the machine. On the top of the box are two lids, D D, opening from the center toward the ends of the box. (One lid, however, may be used, though I prefer two.) Upon the undersides of the lids are secured a series of triangular-shaped ribs, E, the perpendicular sides *a* of which ribs are rounded off, for a purpose hereinafter mentioned, and the sides *b* of which are waved or scalloped, as shown in the drawings. These ribs are so arranged that their apices shall stand toward each other, leaving a space, F, Fig. 2, between them for the reception of the clothes to be washed, or a part of them. A button, G, holds the lids tightly closed while the washing is being done. Against the ends of the box, and on the inside thereof, are vertical ribs *c*, of an angular form in their cross section, as shown in Fig. 3, though they may be rounded off instead of angular.

The reciprocating washing block or frame is constructed as follows: A series of ribs, *d*, are fastened to a bottom piece, *e*, and side pieces, *f*, may also be attached thereto, so that there shall be a chamber, *g*, in which a portion of the clothes to be washed may be placed. The top edges of the ribs *d* are waved or scalloped, and their ends scarfed or rounded off, so as to pass in between the stationary ribs *c* on the ends

of the wash-box, and the bottom piece, *e*, is also scalloped out, as shown at *i*, so that it may come close up to the end of the box, thus allowing the ribs to overlap or pass by each other.

In the smaller-sized machines, or for light washing, the washing block or frame will move easily enough by simply rocking the machine on its rockers *c*; but for larger-sized machines, or for heavier washing, I propose to place friction-rollers on the bottom or sides, or both, and arrange ways or guides for them to roll on or against; or they may roll against the bottom and sides of the box itself.

The clothes to be washed may be placed in the receptacle *F* *g* or in the spaces *h h*, or portions of them in each place. Those in *F* *g* are washed between the ribs *E d*, and those in the spaces *h h* between the ends of the ribs *d* and the ribs *c*. Thus three distinct washings of clothes of different degrees of fineness may be going on at the same time, each lot being subjected to the action of a series of movable ribs working past or against a series of stationary ribs.

To put the machine in motion, it is only necessary to rock it on its rockers. The water dashes through the clothes, while the ribs loosen up all the unclean matter in them, the water taking up all the dirt. The washing-surfaces being rounded or scalloped, the clothes are subjected to an action no greater or more wearing upon them than that of hand-washing on a common hand-board, while the saving of labor to the operator and the expedition with which the washing is done is greatly in favor of the machine.

The machine is quite simple and cheap, and there are no parts of it likely to get out of order or to wear out. By placing the ribs *E* upon the lids the opening up of the lids removes the ribs out of the way and admits of the ready placing in or removing of the clothes.

Having thus fully described the nature and object of my invention, what I claim therein as new, and desire to secure by Letters Patent, is—

In combination with the wash-box and washing block or frame, the ribs *E d c*, arranged to operate in connection with each other in the manner substantially as and for the purpose set forth.

JAMES K. WHITESIDE.
